UNITED STATES PATENT OFFICE.

JOSEPH W. TAGGART, OF WATERTOWN, NEW YORK, ASSIGNOR TO TAGGART BROTHERS COMPANY, OF WATERTOWN, NEW YORK, A CORPORATION OF NEW YORK.

PAPER-BAG PRESS.

Application filed September 26, 1921. Serial No. 503,372.

To all whom it may concern:

Be it known that I, JOSEPH W. TAGGART, a citizen of the United States, residing at Watertown, in the county of Jefferson and 5 State of New York, have invented certain new and useful Improvements in Paper-Bag Presses, of which the following is a specification.

This invention relates to a press, designed 10 for use in connection with the ending machines employed in paper bag manufacture, and has for its object to provide novel, simple and effective means for applying pressure to the newly pasted bags after they 15 are ejected from the ending machines, the arrangement of the press being such that the bags are subjected to the pressure for several minutes while the paste is drying. A further object is to provide a device of 20 the class which is operatively connected to the ending machine and has a plurality of registering press rolls which co-operate with belts for successively gripping and pressing the bags as they are carried through the 25 device, certain of the rolls being self-adjusting and exerting pressure in proportion to their weight entirely by gravity. A further object is to provide novel and simple means for effecting the successive overlapping of 30 the freshly pasted bags in close arrangement for prolonging their travel through the press, and for rotating the several rolls step-by-step corresponding to the spacing of the bags. And a further object is to provide 35 novel and convenient means for manually operating the belts for ejecting the bags that remain in the press after the ending machine has ceased its operation.

I attain these objects by the means set 40 forth in the detailed description which follows, and as illustrated by the accompanying drawings, in which—

Figure 1 is a side elevation of the complete machine showing the same in the act of pressing a large number of freshly pasted bags. Fig. 2 is an enlarged fragmentary side view taken between the broken lines 2—2 of Fig. 45 1. Fig. 3 is respectively a face and an edge view of one of the bags. Fig. 4 is a top 50 plan view of the press, in which certain of the belts are broken away for showing the disposition and arrangement of the gravitational and other press rolls. And Figs. 5, 6 and 7 are similar attached views of the 55 larger and smaller gravitational rolls.

In the drawings, 2 represents the side rails of the main frame which are tied together by cross-rails 2', and are also supported by legs 2^a—2^b, preferably of different lengths for inclining the machine. 3—3 represent 60 similar but lighter side rails of a superimposed frame, which are rigidly mounted on and spaced above the rails 2 by a number of short legs 3'. The bag-ending machine is not shown, but the lowermost end of the 65 press is preferably placed adjacent the said machine, so that the freshly pasted bags, as they leave the ending machine, may readily gravitate into and down a receiving chute 5, which is supported by the top frame 3—3. 70 As the bags 4 are ejected from the ending machine, their freshly pasted bottom ends face the press, and upon reaching the bottom of the chute 5, land upon a broad carrier belt 6, which is operatively supported by a 75 relatively broad face pulley at each end of the press. These pulleys 6' and 6^a are mounted on shafts 6^b and 6^c which are journaled in bearings carried by the rails 2—2. The relatively long span of the top portion of the belt 6 80 between the pulleys 6' and 6^a is preferably supported by a plurality of idler rollers 6^d, which are journaled in bearings 6^e carried by the rails 2—2. The shaft 6^c of the pulley 6^a supports a spur-gear 6^f, which meshes with 85 and is driven by a similar gear 7 mounted upon and operated by a shaft 7'. The opposite end of shaft 7' supports a ratchet-gear 7^a and a hand wheel 7^b. The shaft 7' is rotated step-by-step for correspondingly 90 jogging the belt 6 by a pawl 7^c, which is carried by a depending lever 7^d, the latter being pivotally supported by the shaft 7'. 8 represents a similar depending lever which is pivoted at 8' to one of the rails 2 near 95 the front end of the press. The levers 7^d and 8 are correspondingly perforated for adjustably connecting a link 8^a. One end of an actuating rod 8^b also connects to lever 8, the opposite end of said rod being operatively connected to parts of the ending machine (not shown), by which the intermittent or jogging motions of the pressing parts are effected, as described.

In order to render more positive the driving of the bag-carrying belt 6, the rear ends of the shafts 6^b—6^c are fitted with pulleys 6^g, which carry and drive a belt 6^x (see Fig. 4). As each freshly pasted bag 4 is ejected from the ending machine and gravitates via 100 110

the chute 5 toward the belt 6, the rods 8^a—8^b are moved longitudinally for rocking the levers 7^a—8 from the full to the dotted line positions shown in Fig. 1, and then back to 5 the full line position. This rotates the ratchet the space of one tooth, and correspondingly moves the belt 6 away from the chute 5 for carrying forward another bag 4 towards the pressing position, and so on.

10 In order to prevent the several folds of the relatively thick and stiff paper comprising the closed ends of the bags 4 from springing apart and breaking the seal after being pasted, it is necessary to subject the 15 said ends to a sustained pressure for several minutes, while the paste or glue is setting and drying. This is accomplished in the present device in a novel and effective manner, as follows: 10 represents a relatively 20 large and heavy press roll, of the nature of a pulley, which is mounted substantially directly above the pulley 6', and is movable therefrom vertically sufficiently to allow a relatively thick layer of the overlapping 25 bags 4 to be disposed between the said pulleys (see Fig. 1). The roll 10, and a similar roll 11 disposed in like manner above the pulley 6^a, carry a pressure belt 10', which with the belt 6 form the path or 30 course for the travel of the bags 4 through the press. The roll 10 is mounted on a shaft 10^a, which is journaled in the corresponding ends of a pair of arms 10^b, the opposite ends of said arms being pivotally 35 mounted by a shaft 10^c in similar bearings 10^d which are carried by the top edges of the frame 3—3. By this construction and arrangement the roll 10 is free to gravitate towards the pulley 6 and to exert its weight 40 and pressure upon the overlapped layer of bags 4 (see Fig. 1), and effects the initial pressure upon said bags. The roller 10 is relatively large in diameter, and the bags 4 readily enter between said roller and the 45 belt 6, and a positive purchase or grip is effected which prevents the bags from shifting, or varying from their regular course and spacing, which is necessary for producing an even and positive pressure upon the 50 freshly pasted ends. In order to aid in effecting the regular and relatively close spacing of the bags 4, as they are automatically fed into the pressing machine, I provide a guard or stop, which may comprise 55 a sheet of metal 12, whose curved lower end is free and extends into the crotch of the roll 10 and the pulley 6', while its upper end is rigidly supported by a cross-bar 12', which is mounted on the top edges of the 60 chute 5. Increasing or decreasing the curvature, as well as changing the angularity of the guard 12 from that shown in Fig. 1, correspondingly varies the spacing of the bags 4. The roller 11 is mounted on a shaft 65 11' which is journaled in the corresponding ends of similar arms 11^a, the latter being pivotally supported by a shaft or rod 11^b having bearings in blocks 11^c, which are also mounted on the frame 3—3. The roller 11, which effects the final pressure on the bags 70 4, is preferably positioned slightly to the rear of the vertical axis of the pulley 6^a, and tends to depress the emerging layer 4 for directing the individual bags into a trough or chute 5', which collects and holds the 75 bags until the operator removes them. The relatively long span between the rolls 10 and 11 is provided with a number of secondary and smaller and heavier press rolls 13, which also exert their pressure by gravity. 80 The rolls 13 are mounted on shafts 13' which are journaled in the corresponding ends of supporting arms 13', whose opposite ends are pivoted to the rails 3—3 by rods 13^b, as best seen in Figs. 1 and 4. The 85 rolls 13 are disposed substantially in the line of the vertical axis of the idlers 6^d and exert their pressure on the lowermost section of belt 10' which rests upon the top faces of the bags 4. The frequency of the 90 rolls 13 and 6^d insures the constant and even pressure on the belt 10' and on the bags 4 while the latter are being slowly jogged through the intermediate portion of the press. It usually requires four or five 95 minutes for each bag 4 to be carried through the press rolls, and when the bags are finally deposited in the chute 5', the pasted ends of the bags are all perfectly sealed and ready for use. 100

Having thus described my invention, what I claim as new and desire to secure by Letters Patent, is—

1. A paper-bag press, including an inclined frame, an inclined bag-carrying belt 105 mounted in the frame, a pressure belt arranged parallel to and spaced above the carrying belt, a plurality of gravitational pressure rolls disposed within the pressure belt and exerting constant pressure upon the articles supported by the carrying belt, and means for intermittently operating both of said belts. 110
2. A paper-bag press, comprising an inclined belt adapted to carry a continuously forming layer of bags, a pair of pulleys for supporting and operating said belt, means for rotating said pulleys step-by-step corresponding to the feeding of the bags into the press, an inclined pressure belt disposed above and parallel to the other belt, gravitational pulleys for operatively supporting the pressure belt, and a plurality of gravitational pressure rolls riding on the pressure belt and distributing their weight along the 115 inclined layer of bags. 120
3. A paper-bag press, including an inclined belt adapted for carrying a continuously forming layer of bags, a pair of pulleys for operating said belt, means for 130

operating said pulleys step-by-step for jogging the bags during the pressing operation, an inclined pressure belt disposed above and parallel to the other belt, gravitational pulleys 5 operatively supporting the pressure belt, and a plurality of gravitational press-rolls disposed between the gravitational pulleys and riding on said pressure belt.

4. A paper-bag press, including an inclined frame, an inclined belt mounted in said frame adapted to carry a layer of freshly pasted bags, a pressure belt arranged parallel to and spaced above said carrier belt, a plurality of gravitational press-rolls disposed 15 within the pressure belt and exerting constant pressure towards the bags and carrying belt, and a mechanism for simultaneously operating said belts step-by-step for prolonging and repeating the compression 20 of the freshly pasted bags.

5. A paper bag press, including an incline frame, similar spaced pulleys journaled in the frame, a belt operatively connecting said pulleys and inclined like the frame adapted 25 to carry a layer of overlapped bags through the press by intermittent stages, means for rotating said pulleys step-by-step, a pressure belt disposed above and parallel to the first belt and normally spaced therefrom, said 30 pressure belt adapted to be driven by frictional contact with the layer of bags, and a plurality of press-rolls exerting their weight by gravity upon the pressure belt for pressing the layer of bags against the lowermost 35 belt.

6. A paper-bag press, including an incline frame, similar spaced pulleys journaled in the frame, a belt operatively connecting said pulleys and inclined like the frame adapted 40 to carry a layer of bags through the press by intermittent stages, means for rotating said pulleys step-by-step for jogging the layer of bags, a pressure belt disposed above and parallel to the first belt and normally 45 spaced therefrom, a pair of spaced gravitational pulleys supporting and actuating said pressure belt, and a plurality of gravitational press rolls interposed between the gravitational pulleys and exerting their weight upon 50 said pressure belt for compressing the layer of bags.

7. In a bag pressing device, an inclined frame, pulleys journaled near the opposite ends of the frame, gears for operating said 55 pulleys step-by-step, a carrier belt operatively supported by said pulleys, a plurality of idler rolls for supporting the intermedi-

ate portion of said belt, a pressure belt disposed above and parallel to the carrier belt and spaced therefrom for providing a path 60 for a layer of bags to be carried through the device, gravitational pulleys supporting said pressure belt, said pulleys and said belt being operated by the frictional contact of the pressure belt with the layer of bags, 65 and a series of gravitational press-rolls registering with the idler rolls adapted to exert pressure on the bags between the gravitational pulleys.

8. A machine for pressing freshly pasted 70 paper bags, comprising a pair of similarly spaced inclined belts disposed one above the other, the lowermost belt adapted to carry a continuously forming layer of the bags, means for effecting the overlapping and 75 regular spacing of the bags as they are fed into the machine, means for intermittently actuating said belts for successively moving the layer of bags corresponding to their spacings, a plurality of press rolls disposed 80 at intervals along the incline above the layer of bags, the uppermost belt being supported by said rolls and said rolls exerting their weight for successively compressing the freshly pasted ends of the bags, and the said 85 weight also creating sufficient frictional contact between the uppermost belt and the layer of bags for effecting the positive driving of said uppermost belt.

9. A machine for pressing paper bags 90 comprising the combination with an inclined frame, and a chute adapted to receive freshly pasted bags from an ending machine, of a pair of belts spaced apart to provide therebetween a path for the bags, said belts being 95 disposed at an incline and parallel to each other, a pair of pulleys supporting the lowermost belt, a train of gears and a ratchet for positively driving said pulleys and the lowermost belt, means for effecting the overlapping and spacing of the bags, means for actuating the ratchet for rotating the pulleys and for moving the lowermost belt step-by-step corresponding to the spacing of the bags, a pair of gravitational pulleys for 100 supporting the uppermost belt, a plurality of gravitational rollers riding on the uppermost belt between the gravitational pulleys, the said uppermost belt and the several gravitational parts being actuated by frictional contact with the layer of bags.

In testimony whereof I affix my signature.

JOSEPH W. TAGGART.
